United States Patent

Des. 236,363
Patented Aug. 19, 1975

236,363

COMBINED TOY TRACKWAY AND GONDOLA

Kazuyuki Hashimoto, Tokyo, Japan, assignor to
Toytown Corporation, Tokyo, Japan

Filed Nov. 20, 1973, Ser. No. 417,505

Term of patent 14 years

Int. Cl. D21—01

U.S. Cl. D34—15 A

FIG. 2

FIG. 5

FIG. 6

FIG. 1 is a perspective view of a combined toy trackway and gondola embodying my new design;

FIG. 2 is a front elevational view thereof;

FIG. 3 is a top plan view thereof;

FIG. 4 is a bottom plan view thereof;

FIG. 5 is a right side elevational view thereof; and
FIG. 6 is a left side elevational view thereof.

I claim:

The ornamental design for a combined toy trackway and gondola, as shown.
